UNITED STATES PATENT OFFICE.

FELIX KAUFER, OF BRÜCKL, AUSTRIA-HUNGARY, AND AUGUST KLAGES, OF SALBKE, GERMANY.

APPARATUS FOR MANUFACTURING MERCURY BICHLORID.

1,082,530.

Specification of Letters Patent.

Patented Dec. 30, 1913.

Original application filed August 27, 1912, Serial No. 717,246. Divided and this application filed March 19, 1913. Serial No. 755,377.

To all whom it may concern:

Be it known that we, FELIX KAUFER, a subject of the Emperor of Austria-Hungary, and resident of Brückl, Carinthia, Austria-Hungary, and AUGUST KLAGES, a subject of the German Emperor, King of Prussia, and resident of Salbke, in the Province of Saxony, Kingdom of Prussia, German Empire, have invented new and useful Improvements in Apparatus for Manufacturing Mercury Bichlorid, of which the following is a full, clear, and exact specification.

The invention relates to apparatus for preparing mercury bichlorid by the direct action of chlorin gas or mercury; and the present application is a division of a prior application filed by us on the 27th day of August, 1912, Serial No. 717,246, in which the invention is shown and described but not specifically claimed.

It has for its object to provide apparatus suitable for continuously burning mercury in a current of chlorin gas and which apparatus may be closed and of small size, whereby the same may be readily surveyed and escape of the mercury bichlorid vapors prevented. Danger to the workmen is thereby obviated, the bichlorid being obtained as a finished commercial product, requiring no crystallization, sublimation or drying of the poisonous substance.

The invention has for its object, furthermore, to obtain mercury bichlorid in an extremely finely divided state and thereby avoid the troublesome pulverization of the solid mass, the product thus obtained, moreover, being chemically pure, of brilliant white color and much more voluminous than that heretofore obtained.

In the accompanying drawings, the apparatus employed for the production of mercury bichlorid is represented in side elevation, partly in section.

a designates the retort preferably consisting of quartz glass and provided with a chlorin admission tube *b* ending above the level of the mercury *c* contained in the retort, and a mercury admission tube *d* terminating below the level of said mercury. Both tubes *b* and *d*, are also preferably made of quartz. As shown in the drawing, the mercury admission tube *d* can be disposed within the chlorin admission tube *b*, the mercury flowing through the tube *d* be-

ing thus preliminarily heated by the chlorin flame burning at the open end of the tube *b*, before said mercury enters the mass of mercury *c*. Both tubes may be provided with suitable valves *e* and *f* for regulating the admission of the chlorin and mercury, respectively.

The retort is heated by suitable means. In the drawing a gas burner *g* is shown, which may be of any desired construction. Other heating devices, for instance electric heating appliances, may be used.

The mercury bichlorid formed in the retort may be discharged through the outlet tube *h* into a large tower *i*, which may be of any suitable material not attacked by the mercury bichlorid vapors. In practice we have found it preferable to use glazed acid-proof bricks. Into this tower air is admitted by means of a tube *k* provided with a suitable regulating valve *l*, the air being preferably mixed with a small percentage of chlorin, not exceeding say 10%. The tube *k* preferably terminates near the end of the outlet tube *h*. Thus the air becomes mixed with the mercury bichlorid vapors and the latter are chilled and transformed into crystalline needles which may be removed through a man-hole provided with a suitable cover *m*.

In order to prevent any loss of mercury bichlorid it is preferable, though not absolutely necessary, to provide a second tower *n* connected to the tower *i* by means of a tube *o*. The tower *n* may also be provided with a man-hole and cover *p*. In this tower, which may be made of clay, the last traces of mercury bichlorid are deposited. The apparatus is, furthermore, provided with a tube *q* connected with a suitable suction device (not shown). Generally it will be sufficient to connect the tube *q* with a chimney; or instead of suction devices, the gases may be introduced under pressure.

The process is rendered continuous by passing the current of chlorin gas continually through the apparatus, and in constantly admitting fresh quantities of mercury to the chlorin flame, burning above the boiling mercury level, by allowing the mercury, which has preferably been preliminarily heated by the said chlorin flame, to enter below the level of the boiling mercury. The reaction is assisted by gentle heating

and the whole reaction vessel is filled with a brilliant green flame. The bichlorid thus formed, drips off as a thin liquid, colorless distillate which very soon solidifies; or, as 5 in the modification, the bichlorid formed by the burning process is transformed into a finely divided state by allowing the mercury bichlorid vapors to escape from the retort *a* to the towers *i* and *n* in which they are 10 chilled with cold air. The vapors thus treated instantaneously solidify in the form of fine voluminous needles, absolutely pure and free from mercury monochlorid, especially if a small percentage of chlorin gas, 15 generally not exceeding approximately 10%, be mixed with the air current. These crystals are much more voluminous than the product obtained heretofore by the usual processes, one liter of the mercury bichlorid 20 thus obtained weighing only 1400 grams, whereas the usual powdered mercury bichlorid weighs 2800 grams per liter.

We do not limit ourselves to the details of the apparatus shown, which may be 25 varied in practice without departing from the scope of the invention.

We claim:—

1. In an apparatus for burning a liquid in a gas the combination of a retort, a gas 30 admission tube, a liquid admission tube, terminating below the normal liquid level in the retort and located inside the gas admission tube, an outlet tube for the product of combustion, and means for heating the retort.
2. In an apparatus for manufacturing mercury bichlorid the combination of a quartz retort, a quartz admission tube for chlorin and a quartz admission tube for 40 mercury, the latter terminating below the normal mercury level in the retort and located inside the chlorin admission tube, an outlet tube for the mercury bichlorid formed in the retort, and means for heating the retort.
3. In an apparatus for manufacturing mercury bichlorid the combination of a retort, a chlorin admission tube, a mercury admission tube, an outlet tube for the mercury bichlorid formed in the retort, means for 50 heating the retort, and means for condensing the mercury bichlorid vapors.
4. In an apparatus for manufacturing mercury bichlorid the combination of a re-

tort, a chlorin admission tube, a mercury 55 admission tube, an outlet tube for the mercury bichlorid formed in the retort, means for heating the retort, a tower into which the outlet tube opens, and means for introducing a current of air into said tower to 60 chill the vapors from said retort.

5. In an apparatus for manufacturing mercury bichlorid the combination of a retort, a chlorin admission tube, a mercury 65 admission tube, an outlet tube for the mercury bichlorid formed in the retort, means for heating the retort, a tower into which the outlet tube opens, and means for introducing air into said tower in a jet discharging across the retort discharge tube. 70

6. In an apparatus for manufacturing mercury bichlorid the combination of a retort, a chlorin admission tube, a mercury admission tube, an outlet tube for the mercury bichlorid formed in the retort, means 75 for heating the retort, and a tower into which the outlet tube opens, and an air admission tube opening into the tower and terminating near the end of the outlet tube to chill the vapors from said retort. 80

7. In an apparatus for manufacturing mercury bichlorid the combination of a quartz retort, a quartz admission tube for chlorin and a quartz admission tube for mercury, the latter terminating below the 85 normal mercury level and located inside the chlorin admission tube, an outlet tube for the mercury bichlorid formed in the retort, means for regulating the admission of chlorin and mercury, means for heating the 90 retort, a condensing tower of glazed acid-proof bricks, and an air admission tube opening into the tower and terminating near the end of the outlet tube to chill the vapors from said retort. 95

In testimony that we claim the foregoing as our invention, we have signed our names in the presence of two subscribing witnesses.
